UNITED STATES PATENT OFFICE.

GEORGE S. LEE, OF HAWTHORNE, NEW JERSEY, ASSIGNOR TO WHEEL
WITHIN WHEEL COMPANY, OF NEW YORK, N. Y., A CORPORATION
OF NEW JERSEY.

VEHICLE-WHEEL.

SPECIFICATION forming part of Letters Patent No. 700,514, dated May 20, 1902.

Application filed November 1, 1901. Serial No. 80,770. (No model.)

To all whom it may concern:

Be it known that I, GEORGE S. LEE, a citizen of the United States of America, residing at Hawthorne, in the county of Passaic and 5 State of New Jersey, have invented certain new and useful Improvements in Vehicle-Wheels, of which the following is a specification, reference being had to the accompanying drawings, forming a part thereof.

10 My invention relates to vehicle-wheels, and particularly to vehicle-wheels of the type described and claimed in United States Letters Patent No. 672,908, of April 30, 1901.

The object of the present invention is to 15 simplify and improve the construction and arrangement of parts in the type of wheel set forth in such patent and to strengthen the wheel, so that it may be applicable to a heavy class of work.

20 I will now proceed to describe a vehicle-wheel embodying my invention and will then point out the novel features in claims.

In the drawings, Figure 1 is a side elevation of a vehicle-wheel embodying my invention. 25 Fig. 2 is a view in central transverse section of the same, the plane of section being taken upon the line 2-2 of Fig. 1. Fig. 3 is another view in central transverse section, the plane of section thereof being taken upon the line 3-3 of Fig. 1. Fig. 4 is an enlarged view in detail of one of the hub-sections employed, a portion of a floating plate, and one of the 30 guide-plates employed. Fig. 5 is a detail view in perspective of one of the intermediate 35 guide-plates removed from the wheel.

My improved wheel comprises two members, one carrying the hub portion, and which, as heretofore, I designate the "hub" member, and the other carrying the outer rim or tire, 40 and which I term the "tire" member. The hub member comprises the hub proper, (herein designated by the reference character 1,) a plurality of spokes 2, radiating therefrom, and a rim 3. The tire member comprises a tire-rim 4, a plurality of spokes 5, and a floating plate 6. The floating plate is provided with a slot or slots 7, and the hub is provided with similar slots or grooves 8 at right angles thereto. 45 Intermediate guide-plates 9, of which one is 50 shown in detail in Fig. 5, are provided and

are arranged between the opposite faces of the floating plate and the inner faces of the hub. The intermediate guide-plates are each provided with tongues 10, projecting therefrom upon opposite sides thereof and at right angles to each other. These tongues are fitted to the grooves or slots 7 8, and the said guide-plates will therefore positively lock the hub and the floating plate against relative rotation of each other, but will permit relative 55 movement of the two members in the plane of rotation of the wheel.

An annular cushioning device, here shown as a flexible inflatable tube 11, is arranged between the rim 3 of the hub member and the 60 tire-rim 4. A supporting-rim 12 is preferably secured to the tire-rim 4 to form a convenient support for the said cushioning device.

The hub proper, 1, comprises herein two separable and separate sections, each having 65 a plurality of oppositely-disposed radial arms. The inner ends of the spokes 2 are arranged between the opposed radial arms and form spacing-pieces therefor. Bolts and nuts 13 engage the said hub-sections and the spokes 70 and secure them together.

The foregoing construction while having the merit of great simplicity provides extreme 75 rigidity and gives the strength necessary for taking care of the severe side strain to which 80 a wheel of this character is liable to be subjected.

The floating plate 6 has a plurality of radially-extending arms, which alternate with the arms of the hub 1. These radial arms are 85 recessed, and the inner ends of the spokes 5 are fitted to such recesses. The spokes 5 are bifurcated and have each two branches which diverge from the inner supported end, and at their outer ends both of the said branches 90 are secured to the tire-rim 4. Each spoke comprises two members secured together, as by bolts and nuts 14. These members are arranged upon opposite sides and surround the cushioning-ring 11. By reference more 95 particularly to Fig. 2 it will be seen that one member of each of the said spokes is secured to the floating plate, while the other member is secured to the first said member by the said bolts or nuts 14. By loosening said bolts 100

or nuts 14 one member of each of the spokes may be removed and access may be obtained to the cushioning-ring 11 without dismantling or entirely disassembling the wheel.

5 I have provided the outer tire-rib 4 with a rubber tread 15, which tread may be employed or omitted, as desired.

It will be noted as a matter of construction that the interior faces of the hub-sections are 10 each in a plane and that the thickness of the floating plate 6 is substantially equal to the distance between the said hub-faces. The floating plate is recessed in order to receive the intermediate guide-plates. This construction simplifies the manufacture of this portion of the wheel and reduces the cost thereof, while at the same time it provides a simple and comparatively light construction, combined with great strength and durability. The movable 15 parts are well protected, and that in a very simple manner, from dust or dirt.

I do not desire to be limited only to the precise details of construction and combination of parts as herein set forth, as the same 20 may obviously be varied within wide limits without departing from the spirit and scope of my invention.

What I claim is—

1. A wheel comprising two relatively movable members, one a tire member and the other a hub member, and having a cushioning device between them, the hub member comprising two hub-sections, a plurality of spokes, and a rim, the said spokes having portions 35 thereof located between the said hub-sections to form spacing-pieces therefor, and secured to the said hub-sections.

2. A wheel comprising two relatively movable members, one a tire member and the other a hub member, and having an annular cushioning device between them, the hub member comprising two hub-sections, each having a plurality of oppositely-disposed radial arms, a spacing-piece between each of 45 the said opposed radial arms, said spacing-pieces comprising the inner ends of spokes, bolts connecting the hub-sections together and passing through said spacing-pieces, and a rim supported by the opposite ends of said 50 spokes.

3. In a wheel, the combination with a hub, spokes and a rim, of a tire-rib, an annular cushioning device between the tire-rib and the first said rim, a floating plate, spokes comprising separable members arranged on either side of the said annular cushioning device, and connecting the said floating plate and tire-rib together, and an intermediate guide-plate between the floating plate and the hub.

60 4. In a wheel, the combination with a hub,

spokes and a rim, of a tire-rib, an annular cushioning device between the tire-rib and the first said rim, a floating plate, spokes comprising, each, two members secured together, and connecting said floating plate and said 65 tire-rib, said members arranged on opposite sides of said annular cushioning device, and an intermediate guide-plate between the floating plate and the hub.

5. In a wheel, the combination with a hub, 70 spokes and a rim, of a tire-rib, an annular cushioning device between the tire-rib and the first said rim, a floating plate, spokes comprising each two members, one member of each spoke secured to the said floating plate 75 and said tire-rib, and arranged to pass on one and the same side of said annular cushioning device, and the other spoke member removably secured to the first said spoke member, and arranged upon the opposite side 80 of said cushioning device, whereby the two members of each said spokes surround said cushioning device; and an intermediate guide-plate between the floating plate and the hub.

6. In a wheel, the combination with a hub, 85 spokes and a rim, of a tire-rib, an annular cushioning device between the tire-rib and the first said rim, a floating plate, spokes radiating from said floating plate, each spoke comprising two members, secured together, 90 and together surrounding the said cushioning device, the said spokes having each two divergent branches, and secured at the outer ends of the said branches to the said tire-rib; and an intermediate guide-plate between the 95 floating plate and the hub.

7. The combination in a wheel comprising two members, of a hub comprising two hub-sections, spacing-pieces between them and secured thereto, said spacing-pieces comprising the inner ends of spokes, a rim to which the outer ends of said spokes are secured, said hub, spokes and rim comprising one of said wheel members; a tire-rib, a floating plate located within said hub, spokes connecting said floating plate with said tire-rib, said spokes comprising separable members, the said tire-rib, floating plate and last-named spokes comprising the other of said 100 wheel members; an annular cushioning device between the rim of said first-named wheel member and the tire-rib of the other said wheel member, and located between the said separable spoke-sections, and an intermediate guide-plate between the said hub 105 and the said floating plate.

GEORGE S. LEE.
